Primary Examiner — Darlington Ly

(57) **CLAIM**

The ornamental design for an air flow generator, as shown and described.

DESCRIPTION

1. Air flow generator
- 1.1. is a front, bottom, and left side perspective view of an air flow generator showing our new design;
- 1.2 is a front elevation view thereof;
- 1.3 is a rear elevation view thereof;
- 1.4 is a top plan view thereof;
- 1.5 is a bottom plan view thereof;
- 1.6 is a left side elevation view thereof; and
- 1.7 is a right side elevation view thereof.
